BALL GAME APPARATUS

Application filed April 3, 1929. Serial No. 352,064.

This invention relates to game apparatus and has particular reference to baseball game apparatus of the type comprising a playing field, a pitching mechanism and a batting mechanism.

An object of the invention is to provide a new and improved pitching mechanism which is simple in construction and by which the player operating such mechanism may 10 vary the delivery speed of the ball and the direction of travel of the ball as it is delivered to the batter.

Another object of the invention is to provide an improved means under the control of 15 the batter for varying the swing of the bat according to the dictates or judgment of the player at bat.

Other objects and advantages of the invention will become apparent from the following 20 description taken in connection with the accompanying drawings in which—Figure 1 is a perspective view of the apparatus embodying this invention; Figure 2 is a fragmental bottom view of the apparatus showing the 25 control means for the pitching mechanism and the control means for the batting mechanism; Figure 3 is a sectional view taken on line 3—3 of Figure 2; Figure 4 is an enlarged fragmental sectional view taken on 30 line 4—4 of Figure 3; Figure 5 is a sectional view taken on line 5—5 of Figure 2; and Figure 6 is a side view of a figure representing 35 one of a plurality of players to be stationed at appropriate points on the field.

Referring to the drawings, the numeral 5 indicates a frame, between the side and end members of which is secured a base plate 6, of 40 suitable material such as metal, upon which is lithographed or otherwise provided the 45 outline of a base ball field which includes the representations of home plate 7, first base 8, second base 9, third base 10 and pitcher's box 11. Within the base plate 6 are formed 50 a plurality of pockets 12 which are so located as to occupy the normal playing positions of the catcher, the infield players and the outfield players. The playing field is provided with a plurality of openings 13 located respectively adjacent the pockets 12, each of 55 which openings is adapted for the reception

of the stem portion 14 of a figure 15, representing a player. Only one of such figures is herein shown, but it will be understood that the figures when set up in playing positions will represent the full number, nine; 55 of a baseball team including the catcher, pitcher, infield players, and outfield players. It will be noted that the position of the players with respect to the pockets 12 and that the crouched position of the figures is such that the miniature ball, shown in dotted lines in Figure 4 and indicated by the numeral 19, will be directed into the pockets when it is propelled across the field and fairly strikes the front of the player, regardless of whether 60 such player be the catcher, pitcher, any one of the infielders or any one of the outfielders. Along the first base and third base foul lines are provided pockets 16 and 17 which are 65 similar to the pockets 12, hereinbefore mentioned. The pockets 16 and 17 may receive chance foul balls, and it is to be noted that in connection with these pockets no provision is made for the association therewith of figures representing players (although the 70 boundary side members or walls of the frame 5 may cause balls to rebound into these pockets) since to provide players for these pockets would be inconsistent with the rules of baseball which provide that no more than 75 nine players to the side shall participate in the game at any one time.

Upon the field are provided a plurality of barriers 20, 21, 22, 23 and 24 which define areas A, B and C, representing one base, two 80 base and three base hits in the event the ball when batted comes to rest in these respective areas. Adjacent the area C, a suitable opening or pocket 25 is provided which represents a home run in the event a batted ball 85 successively passes the above-mentioned barriers 20 to 24 inclusive and enters that opening or pocket.

Delivery of the ball from the pitcher's box to the batter is accomplished by a pitching mechanism adapted to be controlled by a person representing or in sympathy with the imaginary team on the field opposing the imaginary team at bat. This delivery mechanism is manually controlled and by 90

proper manipulation thereof the speed of the ball may be varied as well as the direction of travel of the ball from pitcher's box to the batter.

5 Referring particularly to Figures 2 to 4, wherein the pitching mechanism is shown in detail, the numeral 27 indicates a ball-impelling member slideably mounted within a pair of yokes 28 suitably connected to the 10 underneath side of the base plate 6. This ball-impelling member is provided at one end with a ball-engaging finger 29 which projects upwardly through an opening 30 formed in the base plate 6 at the rear of the 15 pitcher's box 11, the other end of the ball-impelling member being provided with an eye through which passes a flat spring 31 having its ends slidably mounted within openings 32 formed in one of a plurality of 20 transverse disposed members 33 upon which the base plate 6 is supported. Secured to the underneath side of the base plate 6 is a plate 34 having an opening 35 formed therein in registration with the opening 30 25 through which the ball-engaging finger 29 projects. To this plate 34 is pivotally connected a pair of triggers 36 and 37, the former of which serves to temporarily retain the ball-impelling member 27 in its retracted 30 position and the latter of which serves to vary the extent of travel of such member when it is released by the trigger 36 and moved forwardly by the spring 31 to deliver the ball. These triggers 36 and 37 are 35 controlled respectively by slideable actuating arms 39 and 40 which are pivotally connected to the respective triggers and extend through opposite sides of the frame 5, they being at their outer ends provided with 40 downwardly turned ends for convenience in operation. By a bow spring 41 looped through openings 42 formed in the arms 39 and 40, such arms are normally urged in opposite directions with the result that the 45 trigger 37 is normally held out of the path of travel of the ball-engaging finger 29 and the trigger 36 is normally held in the path of travel of such finger. Although the trigger 36 is normally held in the path of 50 movement of the ball-engaging finger 29, such trigger is cammed out of such position as the ball-impelling member is retracted, the camming action being set up between the ball-engaging finger 29 and the inclined forward face 44 of the trigger. As the ball- 55 engaging finger 29 passes over the inclined face 44 of the trigger 36, the trigger is moved by the spring 41 into a position in front of the ball-engaging finger 29, thereby 60 temporarily locking the ball-impelling member 27 in retracted position against the influence of the spring 31. To release the ball-impelling member 27, thus causing the ball to be delivered from its position in 65 front of the ball-engaging finger 29 to the

batter, the arm 39 is moved inwardly by an operator against the influence of the spring 41. Upon thus releasing the ball-impelling member 27, such member together with the ball-engaging finger 29 is moved forwardly 70 under the influence of the spring 31 until the finger 29 engages the forward end of the slot 30 formed in the base plate 6 through which such finger projects. Should the operator desire to limit the forward movement 75 of the ball-engaging finger 29 to less than its normal extent of travel, the trigger 37 is moved inwardly by the arm 40 against the influence of the spring 41, thereby placing one or the other of the shoulders 46 and 47 provided on the trigger 37 in the path of travel of such finger. In the event a movement of the ball-impelling member 27 which is slightly less than its normal extent of 80 movement, is desired, the trigger 37 is moved inwardly a sufficient distance to place only the shoulder 46 in the path of travel of the ball-engaging finger 29. However, should a further limitation to the forward movement of the ball-impelling member 27 be 85 desired, the trigger 37 is moved inwardly a sufficient distance to place the shoulder 47 in the path of travel of the ball-engaging finger 29. By the construction shown and thus far described, it will appear that three 90 limits of forward movement are provided for the ball-impelling member 27, one being determined by the forward end of the slot 30 formed in the base plate 6 through which the ball-engaging finger 29 projects, another being determined by the notch 46 on the trigger 37, and still another being provided by the notch 47, also provided on that trigger. Therefore, it follows that three 95 degrees of delivery speed of the ball, as it is propelled from a position in front of the ball-engaging finger 29 to the batter, are made possible, any one of which speeds may be pre-selected by the operator in control of the ball-delivering mechanism before executing the delivery.

The batting mechanism includes a shaft 49, journaled in the base plate 6 at one side of the home plate and carrying radially thereon a bat 50 which is held in a retracted position by an operator, representing or in sympathy with the team at bat, there being a handle 51 protruding from the shaft 49 for enabling the bat to be readily retracted and so held until a strike at the ball is to be effected. For limiting the movement of the bat 50 to its retracted position a stop 52 may be provided, and for limiting the normal throw or forward movement of the bat a similar stop 53 is provided, such stops being suitably secured to the base plate 6. The forward swing of the bat 50 is affected by a spring 54 suitably connected to one of the transverse frame members 33, upon which the base plate 6 is supported, the free end of such 100

home plate, and means for supporting the ball in front of said impelling member and for shifting the relative positions of the ball and impelling member whereby the impelling member may be applied to the ball at different points to effect its delivery along selected lines of travel from the pitcher's box to the home plate.

2. In a ball game apparatus, a ball, a playing field having a pitcher's box and a home plate, a ball-impelling member for delivering the ball from the pitcher's box to the home plate along a definite line of travel, and means for supporting the ball in front of said impelling member and for shifting the ball transversely of said definite line of travel in opposite directions and with respect to said ball-impelling member whereby the impelling member may be applied to the ball at different points to effect its deviation from said definite line at one side or the other thereof.

3. In a ball game apparatus, a ball, a playing field having a pitcher's box and a home plate, a ball-impelling member for delivering the ball from the pitcher's box to the home plate, means for supporting the ball in front of said impelling member and for shifting the relative positions of the ball and impelling member whereby the impelling member may be applied to the ball at different points to effect its delivery along selected lines of travel from the pitcher's box to the home plate, and speed control means co-operating with said ball-impelling means for varying the speed of delivery of the ball from the pitcher's box towards the home plate.

4. In a ball game apparatus, a playing field having a pitcher's box and a home plate, a spring-actuated ball-impelling device for delivering a ball from said pitcher's box towards said home plate along a definite line of travel, a ball-supporting member located in front of said ball-impelling device for there supporting the ball to be delivered, said ball-supporting member being movable transversely of said field and relative to said ball-impelling device for causing the ball to deviate from said definite line of travel as it is delivered from the pitcher's box towards the home plate.

5. In a ball game apparatus, a playing field having a pitcher's box and a home plate, a spring-actuated ball-impelling device for delivering a ball from said pitcher's box towards said home plate along a definite line of travel, and a ball-supporting member having a portion exposed through the playing field at a point in front of the ball-impelling device and there adapted to support the ball to be delivered, said ball-supporting member being movable in both directions transversely of said field for correspondingly shifting said ball with respect to said ball-delivering device whereby the ball is caused

to deviate in one direction, on the one hand and in the other direction, on the other hand, from said definite line of travel.

6. In a ball game apparatus, a playing field having a pitcher's box and a home plate, a spring-actuated ball-impelling device for delivering a ball from said pitcher's box towards said home plate, a ball-supporting member located in front of said ball-impelling device for there supporting the ball to be delivered, said ball-supporting member being movable transversely of said field and relative to said ball-impelling device for causing the ball to deviate from said definite line of travel as it is delivered from the pitcher's box towards the home plate, and spring means tending to maintain said ball-supporting member with the ball thereon in a neutral position whereby such ball when delivered is caused to follow a definite line of travel.

7. In a ball game apparatus, a playing field having a pitcher's box and a home plate, a ball-impelling member for delivering the ball from the pitcher's box to the home plate along a definite line of travel, means operable at will for causing said ball to deviate from said definite line of travel, a bat adapted to be actuated through a full swing, and means within the control of an operator for stopping the movement of said bat before it reaches the end of a full swing.

8. In a ball game apparatus; a playing field having a pitcher's box and a home plate; a ball-impelling member for delivering the ball from the pitcher's box to the home plate along a definite line of travel; means operable at will for causing the said ball to deviate from said definite line of travel; a bat adapted to be actuated through a full swing; and bat-limiting means within the control of an operator for stopping the movement of said bat before it reaches the end of a full swing, said bat-limiting means including a stop member movable with said bat, and a manually operated rod adapted to be moved into the path of movement of said stop member.

9. In a ball game apparatus; a playing field having a pitcher's box and a home plate; a ball-impelling member for delivering the ball from the pitcher's box to the home plate along a definite line of travel; means operable at will for causing the said ball to deviate from said definite line of travel; a bat adapted to be actuated through a full swing; and means within the control of an operator for limiting the movement of said bat to less than a full swing, said bat-limiting means including a stop member movable with said bat, a manually operated rod adapted to be moved into the path of movement of said stop member and spring means tending to normally maintain said rod out of the path of said stop member.

spring being connected to a cord or string 55 which is wrapped around the lower end of the shaft 49 and suitably anchored thereto. In order that the player at bat may limit the forward swing of the bat 50 to a position preferably substantially at right angles to the line of delivery of the ball, a bat-limiting means is provided which includes a stop member 56, secured to the lower end of the shaft 49 and adapted to cooperate with a slideable rod 57 under the control of the player representing the team at bat. This rod 57 is slideably mounted within a U-shaped bracket 58, secured to the rear end member of the frame 5, and carries a compression spring 59, one end of which engages a collar 60 secured to the rod 57, and the other end of which engages the connecting portion of the U-shaped bracket through which the inner end of the rod 57 projects. The length of the arm 56 is such that when the rod 57 is retracted, as shown, the bat 50 is free to undergo a full swing from its retracted position to a position in contact with the stop 53. However, when the rod 57 is depressed, the swing of the bat 57 from its retracted position is limited in its movement and is brought to rest in a position directly over the home plate 7, or, in other words, its forward movement is stopped at such time as the bat reaches a position at substantially right angles to the line of delivery of the ball from the pitcher's box to the batter. By making use of the limited throw of the bat, the delivered ball may be hit in a fashion simulating a bunt, which, under certain circumstances, depending upon the number of men on base and the relation of such men to each other, may be desirable as well as justifiable by the player representing the team at bat.

From the nature of the apparatus and the mode of operation of the same thus far described, it will be appreciated that the success of a player, representing his team at play, as against another player, representing his team at play, will depend upon the skill with which the pitching mechanism and batting mechanism are operated, and the greater the skill of two contesting operators the more fascinating will become the contest not only as between the contestants themselves but also as to interested witnesses to such contest.

In order that further skill may be employed by the operator representing the team at bat, as well as by the operator representing the team in the field, I have provided means under the control of the operator of the pitching mechanism whereby the direction of travel of the ball from the pitcher's box to the batter can be deviated one way or the other from a straight line, passing centrally through the pitcher's box and the home plate. This ball deviating control includes a slideable ball-supporting member 62 which extends transversely across the underneath side

of the base plate 6 at a position in front of the ball-engaging finger 29. The ball-supporting member is suitably supported with respect to the underneath side of the base plate 6 and its opposite ends project through the side members of the frame 5 and are there turned down to provide for easy manipulation of such member by the player in control of the pitching mechanism. Normally the ball-supporting member 62 is held in a neutral position by a pair of tension springs 63 which are anchored to one of the transverse frame members 33 and to the ball-supporting member at points in proximity to its opposite ends. An intermediate portion of the ball-supporting member 62 is exposed through an opening 64 formed in the base plate 6 at a point immediately in front of the ball-engaging finger 29, such exposed portion being provided with a detent or opening 65 in which the ball 19 is placed preparatory to its being delivered to the batter, the opening 64 being sufficiently large to permit a slight transverse movement of the ball in one direction or the other at the front of the ball-engaging finger when the ball-supporting member 62 is similarly moved by the operator in control of the pitching mechanism. A slight movement of the ball-supporting member 62 to the left as viewed from the outfield end of the apparatus shown in Figure 1 will result in the ball being struck by the ball-engaging finger 29 slightly to the right, and due to this off-center impact the ball will be delivered to the batter on a line diverging to the left from a straight line passing centrally through the home plate and pitcher's box. On the other hand, if the ball is shifted to the right, as viewed from the outfield end of the apparatus shown in Figure 1, the impact will be delivered by the ball-engaging finger 29 to an off-center position of the ball at the left thereof, thereby causing the ball as it is delivered to the batter to deviate to the right of a straight line passing centrally through the home plate and pitcher's box. Deviation of the ball to the left and to the right, as described, corresponds respectively to the delivering of out curves and in curves, and the degree to which such deviation may be effected depends, of course, upon the extent to which the ball has been moved to the right or to the left by the ball-supporting member 62 before the impact is delivered thereto by the ball-engaging member 29.

While I have shown only one form of the invention, it will be understood that various changes may be made without departing from the spirit of the invention or the scope of the following claims.

What is claimed is:

1. In a ball game apparatus, a ball, a playing field having a pitcher's box and a home plate, a ball-impelling member for delivering the ball from the pitcher's box to the

10. In a ball game apparatus, a playing field having a pitcher's box and a home plate, a ball-impelling member for delivering the ball from the pitcher's box to the home plate along a definite line of travel, means operable at will for causing said ball to deviate from said definite line of travel, speed control means cooperating with said ball-impelling means for varying the speed of delivery of the ball from the pitcher's box towards the home plate, a bat adapted to be actuated through a full swing, and means within the control of an operator for stopping the movement of said bat before it reaches the end of a full swing.

11. In a ball game apparatus; a playing field having a pitcher's box and a home plate; a ball-impelling member for delivering the ball from the pitcher's box to the home plate along a definite line of travel; means operable at will for causing said ball to deviate from said definite line of travel; speed control means cooperating with said ball-impelling means for varying the speed of delivery of the ball from the pitcher's box towards the home plate, a bat adapted to be actuated through a full swing; and bat-limiting means within the control of an operator for stopping the movement of said bat before it reaches the end of a full swing, said bat-limiting means including a stop member carried by said bat and a manually operated rod adapted to be moved into the path of movement of said stop.

12. In a ball game apparatus; a playing field having a pitcher's box and a home plate; a ball-impelling member for delivering the ball from the pitcher's box to the home plate along a definite line of travel; and means operable at will for causing the said ball to deviate from said definite line of travel; speed control means cooperating with said ball-impelling means for varying the speed of delivery of the ball from the pitcher's box towards the home plate, a bat adapted to be actuated through a full swing; and means within the control of an operator for limiting the movement of said bat to less than a full swing, said bat-limiting means including a stop member carried by said bat and a manually operated rod adapted to be moved into the path of movement of said stop, and spring means tending to normally maintain said rod out of the path of said stop member.

In testimony whereof, I have affixed my signature to this specification.

ALEXANDER WEINBERG.
